3,209,625 JEWELER'S TOOL

Norman P. Lowry, Wilmington, Del.; Louise B. Lowry, administratrix of the estate of said Norman P. Lowry, deceased, assignor to Louise B. Lowry, Drexel Hill, Pa.
Filed July 13, 1962, Ser. No. 209,651
4 Claims. (Cl. 81—7)

This invention relates to a jeweler's tool, and more particularly, it relates to a device for use by watch repairman in oiling and replacing the shock-proof balance jewel assembly after the parts have been cleaned and are ready to be replaced in the watch movement.

In repairing or maintaining watches the repairman has, almost with every repair job, the troublesome operation of oiling and replacing the cap jewel to the balance hole jewel of the shock-proof assembly. It will be appreciated that the jewels shown in the accompanying drawings are many, many times larger than their actual size and that in view of the very small size of the jewels most watch repairmen have trouble preventing the dropping, loss, or accidental displacement of the jewels when the job is in progress. Further, the oiling job involves a minute amount of oil which is to be accurately placed and again in view of the delicate nature of the jewels smearing them with oil frequently occurs inadvertently, making it necessary to clean and re-oil the jewels again. All of this involves a loss of time and expense. An efficient method and device for rapid oiling and assembling has long been needed.

Accordingly, an object of this invention is the provision of a device which provides for the exact placement of the jewels in proper relationship with each other and with a proper placement of the oil therebetween so that the two jewels are in optimum sealing and oiling relationship with each other. Another purpose is the provision of a device which affords the handling of a multiplicity of jewels which are to be aligned and which may be, in their respective relationships, of different sizes as to other jewels being simultaneously handled. A still further aim is the provision of an implement which permits the separate holding of the various bearing parts, the alignment of the said parts and the ready removal of the aligned parts as a unit. These and other objectives will appear hereinafter.

In the drawings, which are given for illustrative purposes only and are not limitative, it is to be understood that the device of this invention and the various parts illustrated are in an enlarged state with respect to the actual device for use in handling jewels by watch repairmen, but that devices smaller or larger than those shown in the figures may be used in such manner as that described hereinafter for appropriately fitting parts. In these figures—

FIGURE 1 is a plan view showing the device in open form;

FIGURE 2 is an end view showing the device in a closed position with the direction of closing being indicated by the arrows;

FIGURE 3 is a cross-sectional view of the closed device showing the cap and the hole jewel in their respective positions in the device and showing the tapping tool about ready to be inserted to bring the two jewels into contact; and

FIGURE 4 is a view similar to that in FIGURE 3 but showing how the tapping tool has forced the cap jewel into sealing and oiling relationship with the balance hole jewel beneath it.

As shown in FIGURE 1 the device of this invention comprises a handle 1 connected to a hinge element 2 by a small rod 3, the hinge element 2 containing a plurality of holes 4 in each of the hinged sections 5 and 6. A

2

given hole in one hinged element has a respective hole in the other hinge element which becomes aligned with it when the two flaps are brought together. For example, hole number 7 in hinge section 5 has hole number 8 in hinge section 6 that lines up with hole number 7 when the hinge section 6 is raised in the direction shown in FIGURE 2, pivoting about hinge 9 as it closes. This closure is shown in FIGURE 2, and the resultant aligned holes are shown in dotted form at 7' and 8' in FIGURE 2.

It will be noted from FIGURE 2 that the hole in section 5 is made by two drillings one larger than the other. The larger drilling is of a size corresponding to the outer diameter of the balance hole jewel 10 shown in FIGURE 3 and is of a height corresponding to the thickness of the balance hole jewel. From the bottom surface of section 5 extending upwardly to join the larger opening in a smaller drilling 11. Similarly, the larger aperture 12 in the hole 8 of section 6 is of a larger diameter than the joining section 13. The larger section in this instance is 20 of a diameter that corresponds to the other diameter of the cap jewel 14 shown in FIGURE 3. This diameter is generally less than the diameter of the balance jewel so that the aligned holes have the configuration shown in FIGURES 2, 3 and 4.

25 In operation, the device of this invention, in open position as shown in FIGURE 1 and being scrupulously clean, is merely placed on the work table and the cap jewels 14 that are to be matched with the balance hole jewels 10 are placed in the proper position in section 6 and their 30 chosen apertures. Similarly, the balance hole jewels 10 that are to be matched with the given cap jewels are placed in their respective positions and the apertures in section 5. In each instance a minute amount of oil 16 is then placed 35 in the proper position usually on the balance hole jewel and being very close to the hole 15 of the balance hole jewel on the top surface of the balance hole jewel, and a minute amount of oil is usually placed on the flat surface of the cap jewel. Section 6 is then rotated to close the device as shown in FIGURES 2 and 3 and in this position the cap jewel 14 is held above and out of contact with the balance hole jewel 10 below it. The oil stands ready 40 to act by surface tension when the two jewels are brought together to keep them together and also to act as an oiling agent for the pivot of the balance that fits up in the aperture 15 in the balance jewel.

The watch repairman then takes the tamper 17, inserts it in hole 13 and pushes the cap jewel 14 downwardly to bring it to bear against the balance hole jewel 10 beneath it. This action forces the oil 16 to spread out 50 as shown in FIGURE 4. The watch repairman then removes the tamper 17, lifts the top hinge 6 off the bottom hinge section 5, reversing the closing direction. The cap jewel 14 is left behind, sitting on top of the hole jewel 10 since the oil 16 holds it to the balance hole jewel. The watch repairman then merely turns the opened device over 55 and inserts the tamper 17 in hole 11 and knocks out the assembled unit. It will be appreciated that the assembled unit comprises the cap jewel 14, the balance hole jewel 10 and the shock-proof housing element 18 in which the balance hole jewel is tightly fit and held there by friction.

The watch repairman, of course, allows the assembly to drop upon a scrupulously clean surface such as a fresh piece of white bond paper, and he is then able to pick up the assembly with the proper tool and place it in the watch.

The devices of this invention may be made from any convenient material such as metals like aluminum or nickel or from plastics such as nylon. Generally all of the holes in a given section of the hinge element will be 65 of the same size, and for simplicity of construction and for facility in use, the holes in the two hinge elements

are of the same size and there are supplied adapters or bushings. The bushings are inserted in the cap jewel section being of the desired size while bushings of the right inside diameter for balance hole jewels will be inserted in that section. These bushings are of common construction being in effect mere rings and for convenience they are not shown. A further advantage in the use of bushings is that the alignment of the holes in the sections is assured. The initial holes are made at the same drilling with the hinge sections closed. New bushings can be installed very simply as a stock of the various sizes is kept on hand and the bushing is merely held in place by a friction fit.

It is also to be appreciated that the device can be simplified by omission of the handle 1 and rod 3 letting the sides of the hinge sections be the gripping means to open and close the device. Or if preferred the hinged plates or one of them could be tapered at the non-working end to afford a handle. Further, other alignment means can be supplied, as, for example, by leaving holes like 7 and 8 unfilled with jewels while filling the other holes 4 there-with and then inserting tamper 17 into such unfilled aligned holes 7 and 8 to bring unhinged plates into alignment. While such equivalents may be used, it is preferred to use the device shown in the drawing because of the very rapid, precise alignment it affords and because of the convenient handling provided by element 1 and 3.

By the use of this device and the operations as described the watch repairman can handle these very small elements with efficiency. Inadvertent dropping, misplacing or losing of the jewels is minimized, and the considerable time loss that is involved in the prior practices is avoided. The device of this invention affords the ready alignment of the jewels and their being held in that alignment with minimum exposure to being contaminated or dislodged. Thus, by the device and methods of this invention watch repairmen are able to do very satisfactory, clean and efficient jobs in a minimum of time.

While the invention has been disclosed herein in connection with certain embodiments and certain structural details, it is clear that changes, modifications or equivalents can be used by those skilled in the art; accordingly, such changes within the principles of this invention are intended to be included within the scope the claims below.

I claim:

1. A jeweler's tool for placing two jewels differing in size into an uncontained, surface tension sealing relationship and into oiling relationship with each other which device comprises two sections adapted to lie separately in the open position and adapted to lie one above the other in the closed position, each section having at least one aperture in it alignable with a co-acting aperture in the other section in the closed position, said co-acting aper-

tures differing in size, one adapted to receive the larger of said two jewels and the other aperture adapted to receive the smaller of said two jewels; access in a given aperture when said sections are in the said open position to place oil on the uppermost face of said jewel held therein; means to place the said sections into said closed, aligned position; and for each aperture a boring through the bottom wall of the section in which it is contained, said boring being in conduit relationship with the given aperture and adapted to receive a tamping means and affording access to a part of the bottom face of the jewel held in said given aperture.

2. A device in accordance with claim 1 in combination with a means to push the said jewels into said sealing and oiling relationship when in the said aligned position and to push the resultant composite out of said tool when the said sections are again in an open, unaligned position.

3. A jeweler's tool for placing two jewels differing in size into an uncontained, surface tension sealing relationship and into oiling relationship with each other which device comprises two sections adapted to lie separately in the open position and adapted to lie one above the other in the closed position, each section having at least one aperture in it alignable with a co-acting aperture in the other section in the closed position, said co-acting apertures differing in size, one adapted to receive the larger of said two jewels and having its inside diameter corresponding closely to the diameter of said larger jewel and the other aperture adapted to receive the smaller of said two jewels and having its inside diameter corresponding closely to the diameter of said smaller jewel; access in a given aperture when said sections are in the said open position to place oil on the uppermost face of said jewel held therein; a hinge joining and placed between said sections affording means to place said sections into and out of said closed, aligned position; and for each aperture a boring through the bottom wall of the section in which it is positioned, said boring being in conduit relationship with the given aperture and adapted to receive a tamping means, and affording access to a part of the bottom face of the jewel held in said given aperture.

4. A jeweler's tool in accordance with claim 3 in combination with a tamper having a diameter less than that of any of said borings.
